CONVERSION OF NAPHTHAS TO MIDDLE
DISTILLATES

Charles Newton Kimberlin, Jr., Henry George Ellert, and
Howard Emerson Merrill, Baton Rouge, La., assignors
to Esso Research and Engineering Company, a corpora-
tion of Delaware

Filed Aug. 18, 1959, Ser. No. 834,455
6 Claims. (Cl. 208—46)

The present invention relates to distillate fuel manu-
facture and it pertains more specifically to the manufac-
ture of high quality distillate fuels such as heating oils,
diesel fuel, jet fuels and the like from naphthas boiling
in the gasoline boiling range.

The principal object of the present invention is to
provide a process for converting low octane and/or un-
stable naphthas into materials of higher value and higher
boiling range.

Hitherto, oil refineries have been generally operated
to maximize naphtha production for use as gasoline
motor fuel. Some naphthas are of substantially lower
octane value than others, but could be blended with high
anti-knock constituents to produce gasoline blends of
acceptable quality. However, with the introduction of
high compression ratio automobile engines, the octane
requirements of gasoline have been steadily increasing,
thus severely narrowing the choice of constituents suit-
able as gasoline blending agents. Thus, much virgin
naphtha and naphthas resulting from catalytic cracking
of gas oil, hitherto used as gasoline blends for engines
of moderate compression ratio, can no longer be used
for this purpose. Similarly, refinery processes such as
fluidized coking of residua, and visbreaking operations
produce naphthas that are unstable and sludge forming,
and are of too high sulfur content for satisfactory use
as fuels.

Concomitant with the increasing accumulation of these
relatively low value naphthas in the refineries, there has
grown up in recent years substantial demands for hy-
drocarbons boiling in the middle distillate range of about
300° to 750° F. The rapid growth of heating oil installa-
tions both here and abroad, and the rapid dieselization
of transportation equipment has caused the supply of
middle distillates to be out of balance with that of motor
gasolines. However, operating crude oil and distillate
refinery processes to maximize middle distillates would
seriously interfere with the production of high quality
naphthas. An object of the present invention is to pro-
vide middle distillate fuels without interfering with maxi-
mum high quality and octane gasoline production.

Thus, heretofore middle distillate fuels have been pro-
duced as by-products in the manufacture of gasoline,
and such fuels of relatively high quality could be obtained
directly from fractions of the virgin crude oil or from
the cracking of virgin crudes. The phenomenal increase
in demand for middle distillate fuels has presented a
serious problem to the oil refining industry.

Middle distillates, or distillate fuels, generally boil in
the range of about 350° to 750° F., the so-called heater
oils boiling in the range of 350° to 550° F., while diesel
fuels boil at about 400° to 650° F.

In accordance with the present invention, refinery im-
balance between gasoline and heating oil demands and
stocks are restored by catalytic conversion of low quality
naphtha fractions into middle distillates. In a sense this
is the reverse of the hitherto trend of petroleum refining
where the gasoline fraction was the desired product, and
where low grade gasoline fractions were upgraded to high
anti-knock material by such processes as reforming or
isomerization.

The present invention involves principally conversion

2

of naphtha into middle distillate by catalytic treatment
with liquid hydrogen fluoride and in the further presence,
if desired, of certain promoters such as boron fluoride or
other halide, iron fluoride, and similar compositions. In
5 one embodiment of the present invention, light virgin
naphtha is directly converted. In another embodiment,
naphtha may be thermally, catalytically or steam cracked
to a relatively low degree of conversion, forming sub-
stantial quantities of olefins which are then passed to
10 the catalytic conversion zone. In still another embodi-
ment, low grade catalytic or coker naphtha is fed di-
rectly into the conversion zone, or is mixed with virgin
or casinghead naphtha prior to conversion.

The catalyst employed in the present invention is an-
15 hydrous liquid HF. This may, particularly when virgin
naphthas are being reacted, be augmented with BF_3 . In
this case from 0 to 60 mol percent, preferably, 25 to
40 mol percent BF_3 based on HF, may be employed.
Lesser amounts of from 0 to 10 mol percent, but pref-
erably, 0 to 2 mol percent BF_3 may be employed in
20 processing the more reactive catalytic and coker naphthas
or other naphthas containing olefins.

Several critical conditions must be maintained in ac-
cordance with the present invention to obtain good yields
of middle distillates. Temperatures must be in the range
such that middle distillates rather than lubricating oil
range material on the one hand, or products boiling lower
than middle distillates on the other, are formed. In gen-
eral, temperatures should be in the range of from about
30 0° to 350° F., preferably, 32° to 250° F. Process
temperature is determined by the nature of the feed, the
catalyst composition and the catalyst concentration.
Normally, temperatures in the range of 160° to 250°
F., preferably, 175° to 225° F. are employed in process-
35 ing virgin naphthas using HF- BF_3 catalyst, while lower
temperatures in the range of 25° to 150° F., preferably,
75° to 125° F. give satisfactory results in processing
catalytic or coker naphthas or other unsaturated feeds.
Pressures are such that at least a portion of the catalyst
40 and the feed are maintained in the liquid phase. Catalyst
to oil ratios are in the range of 0.1 to 5/1, and pref-
erably 0.5 to 2.5/1, and contact times to 5 to 180 minutes
are maintained. Again, these conditions will be deter-
mined by the reactivity of the naphtha feed, high catalyst
45 to oil ratios and long contact times being required with
virgin naphthas with low catalyst to oil ratios and short
contact times being satisfactory for the conversion of
catalytic or coker naphthas. Specifically, catalyst to oil
ratios of 1 to 5/1, preferably 2 to 4/1, and contact times
50 of 30 to 180 minutes, generally 30 to 120 minutes, are
employed in processing virgin naphthas. For catalytic
and coker naphthas, catalyst to oil ratios of 0.1 to 1.5/1
and contact times of 5 to 30 minutes are normally satis-
factory.

55 An important problem arising out of the reaction and
reaction conditions heretofore described is the formation
of secondary reaction products, and in particular the
formation of dry gases, principally propane and isobutane,
decreasing the ultimate yield of desired product. It has
60 been found that the yield of desfined middle distillates
can be increased by passing these light products back to
the reaction zone where either through mass action effects
or through their reaction with the catalyst system present,
they are converted into middle distillate. Surprisingly,
65 however, it has been found that if a portion of the de-
sired middle distillate product itself is recycled, on the
order of 2 to 40% based on feed, the formation of the
light material is greatly reduced.

70 The objects of the invention and its advantages will
be more readily apparent from the more detailed descrip-
tion hereinafter when read in conjunction with the ac-

companying drawing showing a preferred embodiment thereof.

Turning now to the figure, a naphtha feed comprising low octane quality constituents, such as virgin naphtha, is admitted through inlet 10, pump 12 and valve 14 into mixer 16. Preferably, prior to admission to 16, the hydrocarbon stream is admixed with concentrated, and preferably anhydrous liquid HF admitted through line 18 and valve 20. The proportion of hydrofluoric acid is preferably in the range of 2 to 4 times by weight of the total hydrocarbon fluids. Mixing of the acid and hydrocarbons may be effected by any one of a number of methods, as by use of special mixers or emulsifiers or by maintaining high linear velocities in the lines.

Preferably, prior to addition of the acid to the hydrocarbon, boron fluoride is added to the former to the extent of 25 to 40 mol percent. In general, if the hydrocarbon feed is moderately or highly olefinic, BF_3 may be omitted, whereas its presence is beneficial and indeed essential when the hydrocarbon feed is low in olefin content, as is the case in virgin naphtha.

The resulting mixture of acid, BF_3 and hydrocarbon is passed to heater 22 wherein it is heated to suitable reaction temperatures of the order of 175° to 225° F., and passed to reaction chamber 24, wherein it is maintained for a period of 30 to 120 minutes at a pressure sufficient to maintain major portions of the catalyst and feed in the liquid phase. Agitation by any known means may be supplied, as by recirculation.

Effluent mixture from reactor 24 is passed through conduit 26 to separator 30 wherein it is separated into two liquid phases as by cooling and gravitation or centrifugal means. The heavier or HF-BF_3 acid phase may be recycled via conduit 32 to pump 34; a portion may continuously be passed to an acid fractionator (not shown) or other means for purifying and restoring the acid, all in a manner known per se.

Returning to the upper layer, the hydrocarbon phase is passed through line 36 to fractionator 38, preferably with pressure release. In accordance with the present invention, the light products, such as the butanes and propane, are recycled to reactor 24 via line 40. Similarly, from 2 to 60% by weight of the desired middle distillate, and which fraction boils between about 250° and 650° F., is recycled via line 42 to reactor 24, while unreacted hydrocarbon naphtha may similarly be recycled via line 44. The middle distillate fraction is passed via line 46 to a finishing plant or for further treatment not forming a part of this invention.

The process of the present invention is further illustrated by the following specific examples.

Example I

A virgin naphtha obtained from a South Louisiana crude and boiling from 215° to 350° F. was treated according to the method outline above. Experimental conditions were:

HF/oil wt. ratio..... 2
 BF_3 /oil wt. ratio..... 0.4
 Temperature, ° F..... 225
 Contact time, hrs..... 2

The reactor was a Monel autoclave equipped with an efficient agitator. The developed pressure was held through the treat. At these conditions the naphtha conversion was 71.6 wt. percent and the wt. percent yields, based on naphtha converted were:

C_3^- 5.6
 C_4^- 39.5
 C_5^- 15.4
 350°/650° F..... 39.5

Example II

A light catalytic naphtha obtained by cracking a South Louisiana crude and boiling from 165° to 350° F. was

treated in a stirred Monel autoclave under the following conditions:

HF/oil wt. ratio..... 0.2
 Temperature, ° F..... 150
 Contact time, hrs..... 0.5

No BF_3 was used. At these conditions 55.3 wt. percent conversion of the naphtha was obtained. The wt. percent yields based on converted naphtha were:

10 C_3^- 0.2
 C_4^- 0.9
 350°/650° F..... 98.9

Example III

The following experimental results were obtained in a statistically planned study on the conversion of naphtha to middle distillate. The experiments were carried out in a Monel autoclave equipped with an efficient agitator. A synthetic blend consisting of 45 wt. percent n-heptane-45 wt. percent n-hexane-10 wt. percent benzene was used to represent a light virgin naphtha feed. Recycle was simulated by charging the respective product fraction with feed.

[225° F., 2 HF/hydrocarbon wt. ratio, 20 wt. percent BF_3 on HF, 2 hr. reaction time]

Feed Composition:				
Naphtha.....	100	50	83	59
Isobutane.....		50		29
250°/650° F.....			17	12
Naphtha Converted to C_3^- and 250° F. +:				
Wt. percent.....	60	45	38	32
Yields, Wt. percent on Naphtha Converted to C_3^- and 250° F. +:				
C_3^-	58.3	51.1	52.6	50
250°/650° F.....	41.7	48.9	47.4	50

It is evident from the above data that middle distillate production is maximized and gas make minimized by recycling at least a portion of the butane or C_4^- and 250° F. + product fractions with unconverted feed.

What is claimed is:

1. An improved process for converting naphthas to hydrocarbons boiling in the middle distillate range of from about 250 to about 650° F. which comprises treating said naphtha in a reaction zone in the liquid phase with anhydrous hydrofluoric acid at a temperature in the range of about 0 to about 350° F., whereby a substantial amount of said naphtha is converted to middle distillates and light hydrocarbons, segregating the product from said reaction zone into light hydrocarbons and middle distillates, and recycling light hydrocarbons, consisting essentially of propane and butanes, and a significant portion of said middle distillates to said reaction zone.

2. An improved process for converting naphthas to hydrocarbons boiling in the middle distillate range of from about 250 to about 650° F. which comprises treating said naphtha in a reaction zone in the liquid phase with anhydrous hydrofluoric acid at a temperature in the range of about 0 to about 350° F., whereby said naphtha is converted to middle distillates boiling in the range of about 250-650° F. and light hydrocarbons, consisting essentially of propane and butanes, segregating the product from the reaction zone into light hydrocarbons and middle distillates, and recycling said light hydrocarbons, and about 2 to 60 percent based on feed of the middle distillate product to said reaction zone.

3. An improved process for converting naphthas boiling in the range of about 165-350° F. into middle distillates which comprises treating said naphtha in a reaction zone in the liquid phase with anhydrous hydrofluoric acid at a temperature in the range of about 32 to 450° F., maintaining the reactants in a catalyst to oil ratio of 0.1-5/1 and at a contact time of 5 to 180 minutes whereby said naphtha is converted to middle distillates boiling in the range of about 250-650° F. and light hydrocarbons, consisting essentially of propane and butanes, segregating the hydrocarbon product from the reaction zone into light

hydrocarbons and middle distillate and recycling said light hydrocarbons and from about 2-60 percent based on feed of said middle distillate product to the reaction zone.

4. The process of claim 3 wherein 0 to 60 mol percent BF_3 , based on HF, is added to said reaction zone.

5. The process of claim 1 wherein said naphtha feed hydrocarbon is substantially paraffinic and about 25 to 40% BF_3 , based on HF, is added to said zone, said temperature being in the range of from about 160° to about 250° F.

6. The process of claim 1 wherein said naphtha feed

contains olefinic hydrocarbons and 0 to 10% BF_3 , based on HF, is added to said zone, said temperature being in the range of about 25° to 150° F.
